ART OF CASKET ORNAMENTATION

Raymond Larson, Chicago, Ill., assignor to Central Metallic Casket Co., Chicago, Ill., a corporation of Illinois

Application April 30, 1936, Serial No. 77,187

12 Claims. (Cl. 41—10)

This invention relates generally to the art of casket ornamentation and has particular reference to certain new and useful improvements relating to the combination of the ornamental elements therefor and the casket-carrying handles.

Generally stated, the principal object of my invention is directed to certain novel features of construction in ornamental plates and corners which ornate elements are adapted to be secured to the side and end panels of the burial container and which novel construction in association with the handle elements affords a wide range of various combinations in the arrangement or relative mounting of such plates, corners and handles to produce different artistic effects in design with a minimum number of standard parts.

An object of my invention resides in the construction of ornate casket plates and corners having integrally formed recesses constituting supports for the casket-carrying handles preferably cooperating with ornate caps and tightening members adapted to secure the plates, corners, handles and caps, in different combinations, to the casket.

Another object of my invention resides in the construction of the ornate corner elements with suitable ornamentation simulating a handle as extending around such corner element or between the recessed portions of the corner element to thereby produce an effect of the continuity of the handle as if the casket handle extended around or through portions of the corner elements.

With the above and other objects in view, my invention consists in the novel construction, combination and arrangement of the parts and members shown in illustrative examples in the attached drawings, described in the following specification and particularly pointed out in the appended claims.

In the drawings:

Fig. 1 is a sectional plan of a casket taken on line 1—1 of Fig. 2 and embodying my invention.

Fig. 2 is a side elevation of the casket;

Fig. 3 is an enlarged section taken on line 3—3 of Fig. 2 showing details of construction of one of the ornamental corners and one of the ornamental side plates and portions of the interconnecting handles.

Fig. 4 is a side elevation of a casket showing ornamental plates and corners of a different design but constructed in accordance with my invention;

Fig. 5 is an enlarged section taken on line 5—5

of Fig. 4 and showing details of construction embodying my invention; and

Figs. 6 to 13 inclusive show diagrammatically several of the various combinations and arrangements which are afforded by my invention.

While the invention is shown in the drawings adapted to a metallic casket, it is obvious that the invention may be readily applied to caskets of other materials, such as wood or concrete, without departing from the spirit of my invention as defined in the appended claims wherein I intend to claim my invention as broadly as the state of the art permits.

The particular or specific designs incorporated in the ornamentation of the several plates and corners is not a part of the invention herein contemplated as it is obvious that the designs and ornamentation may be varied and that my invention may be adapted to such varied or different designs.

In the illustrative adaptation of my invention shown in Figs. 1 to 3 inclusive, the casket generally indicated by numeral 15 includes the side walls 15^A and end walls 15^B which constitute wall panels to which are attached the ornamental handle-supporting plates 16 and corners 17.

The ornamental plates 16, as shown in Figs. 1, 2 and 3, each constitute a hollow or shell-like metallic casting, the marginal rim of the rear side being flattened for attachment to the wall panels as by bolts 18. Each plate 16 is provided, in its front face, with a horizontal passage 16^A preferably of a cross-sectional configuration suited to the cross-section of the handle 19 which extends therethrough.

Obviously, the handle 19 may be made of any suitable material or design or construction. I have preferred to illustrate the handle 19 as made of comparatively lightweight crimped metal having a reinforcing core 19^A of wood.

The ornamental corners 17, as shown in Figs. 1, 2 and 3, each consist of a hollow or shell-like metallic casting having a substantially right-angledly formed rear wall which is adapted to be secured to the casket corner, as by bolts 21. Each corner 17 is provided, in its front face portion, with recesses 17^A adapted to receive the ends of the casket side and end handles 19, and the recesses 17^A are preferably open on the rear side of the corner piece 17 to facilitate installation thereof and preferably also of a cross-sectional configuration to suit that of the handles 19.

As clearly shown in Fig. 3, the supports for the handle 19 in the ornamental plates 16 and corners 17 are disposed a spaced distance from the out-

side face of the casket wall for convenient handling of the casket and the handle 19 is rigidly supported on such ornamental plates and corners, and, as shown in Fig. 1, constitutes a substantially continuous handle extending around the casket.

It will be noted that the effect of the continuity of the handle is carried out in the design of the corner elements by ornamentation simulating a handle as extending around such corner elements or between the portions recessed for the handle and this is an important feature of my invention.

The plates 16 and corners 17, as well as the handles 19, are preferably drilled to receive wood screws 20 which rigidly secure the handles to such ornamental elements.

In the adaptation of my invention illustrated in Figs. 4 and 5, the casket 15 is shown provided with cast metallic ornamental corners 22 and ornamental plates 23 and 23' connected by the side and end handles 19.

The ornamental plates 23 and 23' are of like design, matched to form right-hand and left-hand pieces, so that when mounted as shown in Fig. 4 the two pieces form a design which is symmetrical about its center line.

The plates 23 and 23' are provided with spaced openings to receive bolts 24 for their securement to the casket walls.

At their handle-attaching ends, the plates 23 and 23' are provided with preferably arcuate recesses 23^A formed by the plate wall portion 23^B which is cast in spaced relation from the integral rear wall portion 23^C. The recesses 23^A are preferably formed of a cross-sectional configuration to suit the cross-sectional form of the handle 19 which rests therein. A separate cap 25 of suitable design is preferably provided and mounted on the handle over the recessed portion 23^A and a securing bolt 26, extending through the cap 25, handle 19, plate walls 23^B, 23^C and casket wall securely holds these elements in place.

The ornamental corners 22, as shown in Figs. 4 and 5, each consist of a hollow or shell-like metallic casting having a substantially right-angularly formed rear wall 22^A which is adapted to engage the corner faces of the casket side and end walls.

At the side ends of the angularly disposed front faces, each corner ornament 22 is provided with preferably arcuate recesses 22^B formed or defined by the integral wall portions 22^C and 22^D and adapted to receive the ends of handles 19. The recesses 22^B are preferably formed of a cross-sectional configuration to suit the cross-section of the handle 19. A suitable cap 27 is provided over the handle end and a securing bolt 26 extending through the cap 27, handle 19, wall portions 22^C and 22^A and through the casket wall rigidly secures the handle and the corner 22 to the casket wall.

Additional shorter bolts 28 are provided for securing the corner 22 to the casket walls.

For purposes of continuity in design and simplicity of construction, I prefer to cast the corner 22 with integral parts 22^E and 22^F simulating, respectively, the handle 19 and cap 27.

I have shown in Figs. 6 to 9 inclusive some of the interesting and novel combinations which are afforded by various arrangements and mounting of the two ornamental units 22 and 23 and the interconnecting handles 19.

In Figs. 10 to 13 inclusive I show interesting and novel combinations made possible with the

right-hand and left-hand patterns of the plate unit 23 and handles 19.

From the above description and attached drawings, it will be readily apparent that there is present in the disclosure made herein, a novel art of casket ornamentation made possible by the novel constructions in the relatively few ornate elements which are adapted to be combined in various artistic combinations with the handles to produce different designs in casket ornamentation.

The different designs shown in the illustrations in Figs. 6 to 9 inclusive, include a standard handle combined with the two differently arranged units 22 and 23. Only two standard castings are required for the corner and plate elements, since the right and left hand units 23 and 23' are actually the same casting but being reversely mounted relatively to each other.

In the several different combinations shown in Figs. 10 to 13 inclusive, the standard handle is combined with various mountings of the standard plate 23.

It will also be noted that the different artistic effects in the designs may be produced by use of the same design of unit plate mounted at the corners of the casket and at the intermediate sections of the side wall panels, as illustrated in Figs. 10 to 13 inclusive, or a harmoniously matched corner unit of different design than that of the intermediate plates may be combined with such plates as shown in Figs. 6 to 9 inclusive.

It is possible that the centrally mounted ornamental plate shown in Fig. 4 could be cast in one piece.

I claim:

1. A casket handle comprising an ornamental corner element supported on the casket side and end walls at each corner thereof, a plurality of intermediate ornamental plates supported on the side walls of the casket, said corner elements and said intermediate plates having integral extensions adapted to support a handle a spaced distance from the outer faces of the side and end walls, a handle on each side of the casket extending from one corner element to the other corner element and supported on the extensions of said intermediate plates, a handle on each end of the casket extending between and supported on the extensions of said corner elements, and means for securing said handles against movement relatively to said corner elements and to said intermediate plates.

2. A casket handle comprising an ornamental element supported on the casket wall at each corner of the casket, a plurality of ornamental plates mounted on the side walls of the casket between said corner elements, said ornamental corner elements and said ornamental plates having extensions adapted to support a handle in spaced distance from the face of the wall, and a handle on each side of the casket extending from one of said corner elements to the other, said handles being supported on said extensions of said corner elements and said plates.

3. An ornamental corner for a casket comprising a cast shell-like metallic body having a right-angularly formed rear extension adapted to embrace the corner of the casket, an ornamental design impressed on the outer face thereof, and recesses formed in outwardly disposed portions of opposite sides of the body adapted to receive ends of the casket handles for attachment thereto.

4. An ornamental corner for a casket comprising a cast shell-like metallic body having a right-angularly formed integral rear extension adapted to embrace the corner of the casket, the exterior face of the body having an ornamental design molded or impressed thereon and recesses formed in outwardly disposed portions of opposite sides of the body adapted to receive ends of the casket handles for attachment thereto, said recesses being formed on the inner side of the ornamental wall portions of the body. 5
5. In an ornamental plate for a casket, and in combination, a cast shell-like metallic body having plane-aligned rear face portions adapted to engage the side wall of the casket and an exterior ornamental face disposed outwardly from the rear face portions, said body having a recess formed in the exterior face adapted to receive the casket handle, a cap adapted to be positioned on the outer side of said handle opposite said recess, and means for securing said cap and handle to said recessed body portion. 10
6. An ornamental plate for a casket comprising a cast shell-like metallic body having rear face portions adapted to engage the corner of the casket and an exterior ornamental face portion disposed outwardly from the rear face portions, said body having horizontal recesses closed at one end and adapted to receive ends of casket handles. 15
7. In casket ornamentation comprising a plurality of spaced ornamental units, said units comprising cast shell-like metallic bodies having plane-aligned rear wall-portions adapted to engage a wall of the casket and integral recessed outer wall-portions disposed forwardly of said rear wall-portions, said recessed wall-portions being adapted to receive portions of the casket handle, caps adapted to be mounted on the outer side of the handle opposite each recess, and a bolt for securing each cap and adjacent handle and unit portion to the casket wall, said bolt passing through the cap, the handle, recessed wall-portion, rear wall-portion and casket wall. 20
8. An ornamental corner for a casket comprising a cast shell-like metallic body having a right-angularly formed rear extension adapted to embrace the corner of the casket, an ornamental design impressed on the outer face thereof, and recesses formed in outwardly disposed portions of opposite sides of the body adapted to receive ends of casket handles for support therein. 25
9. An ornamental corner for a casket comprising a cast shell-like metallic body having a right-angularly formed integral rear extension adapted to embrace the corner of the casket, an ornamental design impressed on the outer face thereof, and recesses formed in outwardly disposed portions of opposite sides of the body adapted to receive ends of casket handles for support therein, said recesses being formed on the inner side of the ornamental wall portions of the body. 30
10. An ornamental corner for a casket comprising a cast shell-like metallic body having a right-angularly formed rear extension adapted to embrace the corner of the casket, an ornamental design impressed on the outer face thereof, and recesses formed in outwardly disposed portions of opposite sides of the body adapted to receive ends of casket handles for support therein, and the outer face of the portion of said body in the plane of said recesses being provided with ornamentation simulating the design of the handle to produce the effect of the continuity of the handle as extending through said outwardly recessed portions of said body and around the outer ornate face of said body. 35
11. A casket handle comprising an ornamental element supported on the casket walls at each corner of the casket, an ornamental plate mounted on each of the two casket side walls between said ornamental corner elements, said corner elements and said plates having recesses formed in outwardly extended portions of the body, a handle extending between said plates and said corner elements and supported in said recesses, caps adapted to be mounted on said handle opposite said recesses, and means for securing said caps and handle to said corner elements and plates. 40
12. An ornamental corner for a casket comprising a cast shell-like body having a right-angularly formed integral rear extension adapted to embrace the corner of the casket, the exterior face of the body having an ornamental design molded or impressed thereon and laterally aligned recesses formed in outwardly disposed portions of opposite sides of the body adapted to receive ends of casket handles. 45

RAYMOND LARSON.
